UNITED STATES PATENT OFFICE.

JULIUS GUTMANN, OF BERLIN, GERMANY, ASSIGNOR TO THE FIRMA FABRIK
FÜR SPEZIALNAHMASCHINEN ACTIEN-GESELLSCHAFT, (PATENTE JULIUS
GUTMANN,) OF ZURICH, SWITZERLAND.

BUTTONHOLE-SEWING MACHINE.

SPECIFICATION forming part of Letters Patent No. 624,792, dated May 9, 1899.

Application filed August 14, 1897. Serial No. 648,319. (No model.)

To all whom it may concern:

Be it known that I, JULIUS GUTMANN, a subject of the Emperor of Germany, residing at Berlin, Germany, have invented certain new and useful Improvements in Buttonhole-Machines; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention has relation to that type of buttonhole-sewing machines organized to first bind the edges of a buttonhole in the usual manner and bar the ends thereof by stitches laid parallel with said edges, or substantially so, as described and shown in United States Letters Patent No. 615,165, granted to me November 29, 1898, the present invention having for its object certain improvements residing chiefly in the provision of means for controlling the feed movements of the work-holder, whereby buttonholes of different lengths can be bound and barred as described, and whereby the number of binding and barring stitches may be varied irrespective of the length and width of the buttonhole, and whereby the barring-strokes are or may be made to interlock with the binding-strokes at the ends of a buttonhole, so as to virtually bar the said binding-strokes also.

As in the machine shown in my said patent above referred to, the work-holder is so arranged as to hold the work with the buttonhole lengthwise of the bed-plate, the needle-bar N' and needle N receiving a vertical reciprocating motion as well as a vibrating motion crosswise of the buttonhole for the formation of the binding-strokes, during which operation the work-holder receives a progressive feed motion lengthwise of said button-hole.

For the formation of the barring-strokes the needle-bar reciprocates vertically only, while the work-holder receives a reciprocating motion lengthwise of the buttonhole and simultaneously therewith a progressive feed

motion crosswise of said buttonhole, the stitch-forming appliances being of any well-known or desired or suitable description.

Figure 1 is a side elevation of a buttonhole-sewing machine embodying my invention and illustrating the parts in their position shortly before the completion of the binding of a buttonhole edge. Figs. 1^a and 1^b are stitch diagrams. Fig. 1^c is a sectional detail view of the work-holder carrier. Fig. 2 is an elevation of the mechanism that controls the feed of the work-holder, the parts being shown in their respective positions immediately before the beginning of the binding of a buttonhole edge. Fig. 2^a is a cross-section of the main driving-shaft at the right of the sleeve thereon. Fig. 3 is an under side view, and Fig. 4 a top plan view, of the bed-plate and the mechanism supported therefrom, the overhanging machine-arm being removed in Fig. 4, said figure also showing diagrammatically by arrows the movements of the work-holder.

The vertical reciprocating motion is imparted to the needle-bar N' from the main driving-shaft a , which has its bearings in the overhanging machine-arm. The vibrating motion is imparted to the needle-bar through its swinging frame N^2 from a shaft i^2 , that is geared to shaft a and has its bearings on one side of the overhanging machine-arm, and the vibratory motion of said needle-bar is stopped by a stop-bar l' , that carries a locking-wedge l at its outer or left end, which engages the swinging needle-bar frame N^2 . Finally, the feed-wheel h receives its progressive rotation from a pawl P , Fig. 3, which is reciprocated by a suitable lever operated or vibrated by a cam-grooved sleeve on the shaft i^2 , said feed-wheel having on its upper face or in a discoidal projection of less diameter than its toothed portion a suitable cam or heart-shaped groove m , from which the work-holder receives its progressive feed motion, all of which mechanism is well known and operates in the usual manner or as described in my patent above referred to.

The work-holder, more specifically described hereinafter, comprises a slide g , having motion both lengthwise and crosswise of the bed-

plate f , and consequently of the buttonhole, and from the under side of said slide depends a post b^7 , that projects through a longitudinal slot in a lower slide S , Figs. 1 and 3. To the 5 post b^7 is pivoted one end of a link L' , whose opposite end carries a bolt that extends through a segmental slot in a lever L and has a nut whereby said link is adjustably secured to said lever, which latter is fulcrumed at l^x 10 to the under side of the bed-plate f and has at its free end a pin p' , carrying a roller, which projects into the aforesaid cam-groove m on feed-wheel h , and from which cam-groove and the aforementioned lever and link the work- 15 holder slide q receives its progressive feed motion lengthwise of the buttonhole in one or the other direction. The slide S , below the bed-plate f and above the feed-wheel h , has motion transversely of said bed-plate or 20 crosswise of the buttonhole on suitable guide-plates p^8 p^9 , Fig. 3, said slide being acted upon by springs S' S , which tend to move the slide in one direction across the bed-plate. The slide S is connected with the slide q , so as to 25 cause the two to move together and to admit of slide q moving lengthwise of the bed-plate independently of said slide S , the two forming cross-slides, whereby I am enabled to dispense with the mechanism for coupling the 30 work-holder to the appliances which impart to it its progressive feed motion in binding a buttonhole edge and uncoupling said work-holder from said mechanism to admit of its reciprocation lengthwise of the buttonhole in 35 barring an end thereof, as described in my patent mentioned above.

To the slide S is secured a pin p^2 , that carries a roller, which under the stress of springs S' S is held against and caused to ride along 40 the outer face of a circular projection n on the feed-wheel h . The projection n has at diametrically opposite points recesses 3 and 3^a, the depth of which gradually increases, said recesses being formed by the inward curvature or convergence of the periphery of 45 said projection at the points referred to, so that as the roller on pin p^2 rides down one incline the slide S follows its movement under the action of the springs S' , thereby gradually 50 moving said slide, and with it the work-holder slide q , crosswise of the buttonhole. When, on the contrary, the roller on pin p^2 rides up the other incline, the slide S will be moved 55 against the stress of its springs S' crosswise of the bed-plate in an opposite direction to the first, as will be readily understood.

The mechanism which controls the feed of the work-holder both lengthwise as well as crosswise of the buttonhole is constructed and 60 organized as follows: On the main driving shaft a is mounted a sleeve a^2 , so as to slide freely thereon and revolve therewith, to which end the said shaft has a longitudinal groove a' for the reception of a spline or key fitting 65 a corresponding groove in the sleeve. One-half of this sleeve a^2 —namely, the right half nearer to the driving end of the machine—

has a left-hand screw-thread a^3 , while the left half or the half nearest to the needle-bar end of the machine has a right-hand screw-thread 70 a^4 . In the right half from the end thereof toward the left the sleeve a^2 is slotted and its bore is of greater diameter than the shaft a for the reception of a second sleeve, on which is formed a longitudinal rib a^5 , which projects into said slot, one side of said rib having the form of a cam or wiper in cross-section, the nose of which lies flush with the thread on the sleeve, or substantially so, said sleeve being adjustable lengthwise in said 80 slot.

On the overhanging machine-arm is fulcrumed a bell-crank lever B , the fulcrum-pin for which projects into said arm and has secured thereto a T-lever B' , the horizontal 85 arms b^2 b^3 of which are provided with a tooth c and c' , respectively, adapted to be brought into engagement with the threads of the right and left threaded portions of the sleeve a^2 , the construction and arrangement being 90 such that both teeth c and c' can at no time be brought simultaneously into engagement with the threads of the portions a^3 a^4 of said sleeve, or, in other words, when one of said teeth engages one of the threaded portions of 95 the sleeve the other is held clear of the teeth of the other portion in whatever position the lever B' may be, whereby all danger of injury to the mechanism is avoided.

The vertical arm b of the angle-lever B is 100 adjustably secured to a stop-bar l' through the medium of a screw-pin 12 passing through a vertical slot 13 in the end of said lever-arm b and a nut 14 on said pin, said bar l' carrying at its forward or left-end a wedge-shaped 105 pin l , adapted to engage the needle-bar frame N^2 in such manner as to lock it against vibration without interfering with the rotation of the shaft i^2 and the cam or other appliance that imparts a vibrating motion to said frame. 110

As hereinbefore stated, the means for locking the needle-bar frame N^2 against vibration are shown and described in my patent hereinbefore referred to.

To the horizontal arm b' of the angle-lever 115 B is pivotally connected a lock-bar e , that has near its lower end a guide-slot e' , Figs. 1, 2, and 4, and below said guide-slot an offset or shoulder e^2 , adapted to seat on the left-hand edge of a longitudinal slot f^x , formed 120 in the bed-plate f of the machine, the bar being normally held to its seat on the bed-plate by a spring e^5 . The said bar extends through the aforesaid slot into the forked end g' of a lever g , Fig. 3, fulcrumed at g^2 to a post on 125 the under side of the bed-plate f , and about midway of its length said lever carries a roller g^3 , Figs. 2 and 3, in the path of two abutments or cam projections h' and h^2 on diametrically opposite sides of the feed-wheel h . 130

On the overhanging machine-arm is secured a bracket d , having a screw-threaded opening, in which works a nut d' , through which and the machine-arm passes loosely a

headed pin d^2 , having a spring d^3 coiled about it between its head and the under side of the nut. The head of the pin d^2 has bearing on the arm b^2 of lever B' , the spring d^3 tending to force said arm downward, the tension of the spring being regulated through the medium of the nut d' .

In the lower part of the guide-slot e' of lock-bar e above the bed-plate f works a lever i , 10 that has a downwardly-projecting lug i^4 at its forward end, Fig. 1, while its rear end is fulcrumed to the end of the lower arm of a two-armed rock-lever i' , that receives motion through the medium of a cam-grooved sleeve i^3 on the exterior shaft i^2 , that vibrates the needle-bar frame N^2 , Fig. 1, hereinbefore referred to, so that the lever i so long as the machine is in operation is continuously reciprocated in the direction of the length of 15 the bed-plate f or lengthwise of the button-hole. There is a spring i^5 , Figs. 1 and 4, the free end of which has bearing on lever i and tends to press the same downward, but is prevented from doing so so long as the lock-bar e is seated on or held to the bed-plate f by its 20 spring e^3 ; but when said lock-bar e is unseated and moved downward in the slot of said bed-plate then under the stress of its spring i^5 the said lever i is caused to follow 25 the movement of the said lock-bar to engage one or the other of two transverse slots k^1 k^2 , formed in a plate k , secured to the work-holder slide q^X , hereinafter described, and whereby the short reciprocating motions 30 lengthwise of the buttonhole in barring an end thereof are imparted to the work-holder without interfering with its progressive feed motion crosswise of the buttonhole, the said slots k^1 and k^2 being for this purpose made 35 of the required length, as shown in Fig. 4.

The work-holder is constructed as follows, reference being had to Figs. 1, 1°, 3, and 4: A main slide q , which has motion both lengthwise and crosswise of the bed-plate and buttonhole, as hereinbefore stated, receives a progressive feed motion lengthwise of the buttonhole in one or the other direction from the eccentric portions of the cam-groove m in feed-wheel h and its like feed motion crosswise of the buttonhole in one or the other direction from the cam-face n on said feed-wheel h , as hereinbefore stated. This slide q has longitudinal guideways, in which is fitted a slide q^X , which has a limited motion in said 45 guideways and has secured thereto the longitudinally-slotted work-support q' . To the right-hand end of the slide q^X is secured the laterally-projecting coupling-plate k , hereinbefore mentioned as provided with the transverse coupling-slots k^1 k^2 . The slide q^X has formed in its upper face an oblong concave recess for the reception of a correspondingly convex boss r^2 on the under side of a coupling-plate r , said recess being slightly 50 longer than the said boss to afford a slight longitudinal motion to plate r independently of slide q^X . The boss r^2 is held in the afore-

said recess in slide q^X by a coiled spring r' , interposed between the coupling-plate r and the plate or carrier that carries the cloth clamp and stretcher, said coupling-plate r being hinged to a pintle q^3 , secured in lugs or ears q^2 on the slide q^X , at the left-hand end thereof, and as the said plate r is likewise hinged to pintle q^3 the spring r' performs the twofold function of coupling the carrier-plate s through plate r by frictional contact with the slide q^X and of holding said carrier s to the work, while by depressing the plate r the cloth-clamp is lifted to admit of the insertion and withdrawal of the work. There is, however, another very important improvement involved in the relative arrangement of the work-holder slides in that the slide q^X , and consequently the work-holder, is constrained to 85 partake of the progressive feed motion of the slide q lengthwise of the buttonhole in the operation of binding an edge thereof and of the like motion crosswise of said button-hole in the operation of barring an end thereof and simultaneously therewith reciprocate lengthwise of said buttonhole in said operation of barring independently of slide q , which motion, as hereinbefore stated, is imparted to slide q^X from vibrating lever i' , lever i , and plate k , whereby I am enabled, as above stated, to dispense with the more or less complicated mechanism described in my patent herein referred to, whereby in the operation of binding the work-holder is coupled to the feed-lever and uncoupled therefrom in the operation of barring in order to enable it to reciprocate lengthwise of the button-hole. 90

On the left of its hinge connection q^3 the work-clamp carrier s is arched, as shown at 105 s' , Fig. 1, and forked at its left end s^2 , the branches of said fork being slotted longitudinally from the left end toward the right, as shown at s^3 in said Fig. 1. To the left end of slide q^X is hinged at q^4 , Figs. 1 and 2, a correspondingly-arched bar t , the left end of which is constructed in the form of an oblong rectangular frame t' , Fig. 4, provided with journals t^2 , that project into the aforesaid slots s^3 , and with bearings s^X at opposite ends 110 for the journals on cloth clamping and stretching jaws t^1 , toothed on the underside of their longitudinal edges and having slight motion in a plane parallel with their longitudinal axis, so as to yield somewhat when pressed down on the work by the spring r' . It will thus be seen that when the carrier s is pressed down against the stress of spring r' the frame t' will be slightly displaced longitudinally in that its journals t^2 slide along the slots s^3 , and when said carrier is released and forced down onto the cloth by its said spring r' the toothed jaws t^1 by reason of their being pivoted in a plane parallel with their longitudinal axis in frame t' will spread laterally, and thereby 115 stretch the cloth and hold it firmly for sewing. 120

In practice I have found that when a machine of the class described and provided with a progressively-revoluble feed-wheel h ,

operated by a ratchet and pawl, is driven very rapidly the movements of said wheel are liable to be irregular in that the momentum of the wheel is apt to revolve the same a greater distance at each impulse of the pawl than is required, or said wheel is liable to be moved backward by the frictional contact of the pawl with the ratchet-teeth of the wheel. In order that this may be effectually avoided, 5 I provide a friction-brake, Figs. 1 and 3; in the form of a band, preferably a steel band-brake o , the ends of which are secured to the arms $o' o''$ of a bell-crank lever, on the fulcrum-pin O of which is secured a radial arm o^3 , against which bears an adjusting-screw p , by means of which the frictional contact of the band with the periphery of the groove in wheel h , in which said band is fitted, can be nicely regulated. 10

In Figs. 1, 3, and 4 I have shown the various mechanisms in their respective positions immediately before the beginning of the binding of a buttonhole edge or immediately before the ending of a barring operation, the 15 feed-controlling sleeve being about to reach the limit of its motion toward the left and the tooth c on arm b^2 of lever B' about to come in contact with the tripping cam-rib a^5 . If it be assumed that a buttonhole is to be sewed by 20 successively binding an edge, barring one end, then binding the opposite edge, and finally barring the opposite end, the operation of the mechanism will be as follows: As the main shaft a revolves and the feed-wheel h receives 25 a progressive feed motion in the direction of arrow, Fig. 3, the pin p' on feed-lever p is passing into the eccentric portion 1 of cam-groove m in said feed-wheel. At the same time the tooth c on lever-arm b^2 of tripping-lever 30 B' is moved out of engagement with the left thread a^3 on right half of controlling-sleeve a^2 , thereby tilting said lever B' against the stress of its spring d^3 toward the left and moving the tooth c' on its arm b^3 into engagement 35 with the right-hand screw-thread a^4 on left half of said controlling-screw a^2 . This movement of the lever B' causes the lever B to swing toward the right, thereby moving the lock-bar l in the same direction, whereby the 40 needle-bar frame N^2 is released and will be vibrated by the mechanism operated from shaft i^2 and reciprocated vertically by the mechanism operated from main shaft a , as is necessary to the formation of the binding-55 stitches. At the same time the lever B lifts the bar e , the lower end of which is guided in the forked end of lever g , and the spring e^3 draws said bar to its seat on the bed-plate f . The bar e at the same time lifts the lever i 60 against the stress of its spring i^5 out of engagement with the left-hand slot k' in coupling-plate k on work-holder slide g^X , which places the parts in condition for binding. As the feed-wheel h and controlling-sleeve a^2 65 revolve the work-holder receives a progressive feed motion toward the left—i. e., lengthwise of the buttonhole, arrow I, Fig. 4—while said

sleeve under the action of tooth c' on lever B' gradually moves in an opposite direction, or toward the right, whereby one edge of a button-hole is bound, the needle-bar vibrating, as heretofore stated, crosswise of the button-hole. These movements of the needle-bar and work-holder continue until the controlling-sleeve a has reached the limit of its motion 70 toward the right, Fig. 2, the levers B and B' being held against vibration and the former lever against the action of its spring d^3 by the lock-bar e . When the sleeve a has reached the limit of its motion toward the left, at which time the pin p' on feed-lever L has entered the concentric portion 1^a of cam-groove m , Fig. 3, thereby stopping the progressive feed motion of the work-holder, simultaneously therewith the cam projection h^2 on feed-wheel h acts upon 75 the roller g^3 on lever g , swings the same toward the right, Fig. 3, and thereby unseats the lock-bar e , which drops. The downward movement of the lock-bar tilts the lever-arm b of lever B' toward the right, whereby the stop-bar l' is moved in the opposite direction to lock the needle-bar frame N^2 against vibration, and as the lever B' is secured to the fulcrum-pin of lever B the former lever will be caused to swing toward the right, this movement being 80 assisted by the spring d^3 , thereby moving the tooth c' out of reach of the right-hand thread on the left half of controlling-sleeve a and the tooth c into engagement with the left-hand thread on the right half of said sleeve. At 85 the same time the lock-bar e as it drops moves the coupling-lever i into engagement with the right-hand slot k^2 in coupling-plate k , and simultaneously with these operations the roller on pin p^2 on slide S , being about to 90 ride down the incline 3 on the projection n on feed-wheel h , causes said slide, under the action of its springs S' , to move crosswise of the buttonhole, arrow II, Fig. 4. The needle-bar reciprocates vertically only. The controlling-sleeve a moves gradually toward the left. The work-holder reciprocates lengthwise of the buttonhole, arrow V, Fig. 4, and simultaneously therewith moves progressively in the direction of arrow II, whereby one end of 95 a buttonhole is barred by stitches laid parallel with its edges or substantially so. These operations continue until the tooth c on lever B' is again lifted clear of the left-hand thread a^3 in the right half of the controlling-screw a^2 , at which time the mechanism described is 100 actuated as above set forth and positioned for binding the opposite edge of the button-hole, during which operation the eccentric portion 2 of the cam-groove m acts upon pin p' of lever L , thereby reversing the direction 105 of progressive feed of the work-holder lengthwise of the buttonhole, arrow III, Fig. 4. When this second edge of the buttonhole is 110 reached the limit of its motion toward the right, the mechanism is actuated, as before described, to bar the opposite end of said buttonhole, the pin p' on feed-lever L lying then 115

in the opposite concentric portion 2^a of cam-groove *m*, while lever *i* is coupled to work-holder through the right-hand slot *k'* in coupling-plate *k*, for purposes stated. Finally, the

5 pin *p*² on the lower slide *S* rides along the inclines 3^a on the circular shoulder or flange *n* on feed-wheel *h*, gradually feeding said slide *S*, together with the work-holder, against the stress of the springs *S'* crosswise of the bed-plate *f* and buttonhole in a direction opposite to the first like feed motion of said slide *S* and work-holder, arrow IV, Fig. 4, thus returning the parts, together with the work, to the starting-point.

15 From what has been said it will be seen that the sleeve *a*², the feed-wheel *h*, and the mechanisms operated thereby control the extent of the feed movements of the work-holder both in binding and in barring—that is to say, the distance to which said work-holder is moved to bind an edge or bar an end of a buttonhole. Hence they determine the length of edge to be bound or barred, while the sleeve *a*² determines the amplitude of the feed movement of the work-holder—that is to say, the amplitude of each step of said movements. Hence the distance between the stitches or the number of stitches made in binding or barring is such that the first and last few bar-30 ring-strokes interlock one or more binding-strokes at the buttonhole ends, Figs. 1^a and 1^b, thus practically barring the edge seams. This is accomplished in that the barring begins the moment the needle leaves the fabric 35 after the last stitch has been laid, and by imparting to the work-holder a reciprocating motion lengthwise of the buttonhole of such amplitude as that the first and last three, more or less, barring-strokes will interlock the end 40 binding-stitch.

As the controlling-sleeve *a*² is not rigidly connected with shaft *a*, it is obvious that a series of such sleeves can be interchangeably used, which sleeves may be of different lengths 45 to suit the length of the buttonhole to be sewed, while the right and left threaded portions *a*³ *a*⁴ of said sleeve may have a greater or less number of threads to the inch to vary the number of stitches made during the said 50 movements of the screw.

Having thus described my invention, what I claim as new therein, and desire to secure by Letters Patent, is—

1. In a buttonhole-sewing machine, the combination with the stitch-forming appliances comprising a reciprocating and vibrating needle-bar, mechanism for periodically stopping the vibration of said needle-bar, the work-holder, feed mechanism for imparting to said 55 work-holder a progressive motion lengthwise of the buttonhole while the needle-bar reciprocates and vibrates, then a progressive motion crosswise of the buttonhole while said needle-bar reciprocates only, and mechanism 60 for reciprocating the work-holder lengthwise of the buttonhole during its progressive motion crosswise thereof; of means for determin-

ing the amplitude of the aforesaid progressive movements of the work-holder, for the purpose set forth.

2. In a buttonhole-sewing machine, the combination with stitch-forming appliances comprising a reciprocating and vibrating needle-bar, mechanism for periodically stopping the vibration of said needle-bar, the work-holder, mechanism for imparting to said work-holder first a progressive feed motion lengthwise of the buttonhole, while the needle-bar reciprocates and vibrates, then a progressive feed motion crosswise of said buttonhole while the needle-bar reciprocates only, said mechanism determining the extent of said progressive movements, and mechanism for imparting to the work-holder a reciprocating motion lengthwise of the buttonhole during its progressive motion crosswise thereof; of a controlling device for determining the amplitude of each step of the aforesaid progressive movements of the work-holder, for the purpose set forth.

3. In a buttonhole-sewing machine, the combination with stitch-forming appliances comprising a reciprocating and vibrating needle-bar, the work-holder, feed mechanism for imparting to said work-holder first a progressive motion lengthwise of the buttonhole while the needle-bar reciprocates and vibrates, then a progressive motion crosswise of the buttonhole while the needle-bar reciprocates only, and mechanism for reciprocating the work-holder lengthwise of the buttonhole during its progressive motion crosswise thereof; of a controlling device for determining the amplitude of the aforesaid progressive movements of the work-holder, and mechanism controlled by said device for periodically stopping the vibration of the needle-bar, for the purpose set forth.

4. In a buttonhole-sewing machine, the combination with stitch-forming appliances comprising a reciprocating and vibrating needle-bar, the work-holder, and feed mechanism for imparting to said work-holder first a progressive motion lengthwise of the buttonhole while the needle-bar reciprocates and vibrates, then a progressive motion crosswise of the buttonhole, while the needle-bar reciprocates only; of a controlling device for determining the amplitude of the aforesaid progressive movements of the work-holder, and appliances controlled by the feed mechanism for imparting to said work-holder a reciprocating motion lengthwise of the buttonhole during its progressive feed motion crosswise thereof, for the purpose set forth.

5. In a buttonhole-sewing machine, the combination with stitch-forming appliances comprising a reciprocating and vibrating needle-bar, the work-holder, and feed mechanism for imparting to said work-holder first a progressive motion lengthwise of the buttonhole while the needle-bar reciprocates and vibrates, then a progressive motion crosswise of said buttonhole while the needle-bar reciprocates only; of a controlling device for determining

the amplitude of the aforesaid progressive movements of the work-holder, and means controlled by the feed mechanism and the aforesaid controlling device for imparting to the 5 work-holder a reciprocating motion lengthwise of the buttonhole during its progressive motion crosswise thereof, for the purpose set forth.

6. In a buttonhole-sewing machine, the combination with a reciprocating and vibrating needle-bar, mechanism for periodically stopping the vibration of said needle-bar, the work-holder, feed mechanism for imparting to said work-holder first a progressive motion 10 lengthwise of the buttonhole while the needle-bar reciprocates and vibrates, then a progressive motion crosswise of said buttonhole while the needle-bar reciprocates only, mechanism for reciprocating the work-holder lengthwise 15 of the buttonhole during its progressive motion crosswise thereof, and mechanism for repeating these operations and reversing the direction of the progressive movements of the work-holder; of a controlling device for determining 20 the amplitude of the aforesaid progressive movements of the work-holder, for the purpose set forth.

7. In a buttonhole-sewing machine, the combination with the stitch-forming appliances 30 comprising a reciprocating and vibrating needle-bar, the work-holder, feed mechanism for imparting to said work-holder first a progressive motion lengthwise of the buttonhole while the needle-bar reciprocates and vibrates, then 35 a progressive motion crosswise of the buttonhole while said needle-bar reciprocates only, and mechanism for reciprocating the work-holder lengthwise of the buttonhole during its progressive motion crosswise thereof; of a 40 revolving and to-and-fro-moving right and left threaded screw and mechanism controlled thereby and determining the amplitude of the aforesaid progressive movements of the work-holder, for the purpose set forth.

45 8. In a buttonhole-sewing machine, the combination with stitch-forming appliances, the work-holder, and feed mechanism for imparting to said work-holder a progressive motion; of the main driving-shaft, a right and left threaded sleeve revolving with and moving endwise on said shaft, and mechanism operated by the sleeve and determining the amplitude of the progressive movements of the work-holder, for the purpose set forth.

55 9. In a buttonhole-sewing machine, the combination with stitch-forming appliances comprising a reciprocating and vibrating needle-bar, the work-holder, a progressively-rotating feed device, mechanism operated by said 60 device to periodically impart to the work-holder a progressive motion lengthwise of the buttonhole, and means for periodically imparting to said work-holder a progressive motion crosswise of the buttonhole; of the main 65 driving-shaft, a right and left threaded sleeve revolving with and moving to and fro on said

shaft, and mechanism controlled by the sleeve and feed device for stopping the vibrations of the needle-bar and simultaneously reciprocating the work-holder lengthwise of the buttonhole during its progressive motion crosswise thereof, for the purpose set forth. 70

10. In a buttonhole-sewing machine, the combination with the main driving-shaft, a right and left threaded sleeve revolving with 75 and having endwise motion on said shaft, the lever B', the horizontal arms of which are provided with a tooth to engage one or the other threaded portion of said sleeve, and an abutment at the outer end of the left-threaded portion in the path of the tooth in engagement therewith and acting upon the same to tilt the lever and move the other tooth into engagement with the right-threaded portion; of stitch-forming appliances comprising a reciprocating and vibrating needle-bar, a lock-bar for locking said needle-bar against vibration, a work-holder, mechanism for imparting a progressive feed motion to said work-holder lengthwise of the buttonhole, and means for 80 moving the lock-bar and allowing the needle-bar to vibrate when the aforesaid lever is tilted, as set forth, for the purpose specified. 85

11. In a buttonhole-sewing machine, the combination with the main driving-shaft, a right and left threaded sleeve revolving with 90 and having endwise motion on said shaft, the lever B', the horizontal arms of which are provided with a tooth to engage one or the other threaded portion of said sleeve, and an abutment at the outer end of the left-threaded portion in the path of the tooth in engagement therewith and acting upon the same to tilt the lever and move the other tooth into engagement with the right-threaded portion; of stitch-forming appliances comprising a reciprocating and vibrating needle-bar, the lever B rocked by aforesaid lever B', a lock-bar secured to said lever B and locking the needle-bar against vibration, a work-holder and mechanism for imparting a progressive feed motion lengthwise of the buttonhole to said work-holder when the lever B' is tilted as set forth, whereby the lock-bar is also moved to allow the needle-bar to vibrate, for the purpose set forth. 100 105 110

12. In a buttonhole-sewing machine, the combination with the main driving-shaft, a right and left threaded sleeve revolving with 115 and having endwise motion on said shaft, the T-lever B' having teeth c and c', a spring tending to tilt the aforesaid lever to move tooth c into engagement and tooth c' out of engagement with said left and right threaded portions respectively; of stitch-forming appliances comprising a reciprocating and vibrating needle-bar, the work-holder, and feed mechanism for imparting to said work-holder progressive feed movements first lengthwise and then crosswise of the buttonhole, a second lever rocked by lever B', a lock-bar connected with said second lever and provided 120 125 130

with an offset seating on a fixed support, a spring to hold said bar to its seat, and means connected with the feed mechanism for unseating said bar whereby, under the stress of its spring, the T-lever is tilted as set forth, mechanism for reciprocating the work-holder lengthwise of the buttonhole during its progressive motion crosswise thereof, and means for simultaneously locking the needle-bar against vibration, for the purposes set forth.

13. In a buttonhole-sewing machine, the combination with the main driving-shaft, a right and left threaded sleeve revolving with and having endwise motion on said shaft, the T-lever B' provided with teeth c c', a spring tending to tilt said lever to move its tooth c into and its tooth c' out of engagement with the left and right threaded portions of the sleeve, respectively, the bell-crank lever B rocked by lever B', the lock-bars e and l' respectively connected with the arms of lever B, said lock-bar e provided with an offset seating on a fixed support, a spring holding said lock-bar e to its seat, and the lever g engaging the lower end of said lock-bar e, and carrying a roller g³; of stitch-forming appliances comprising a reciprocating and vibrating needle-bar, the work-holder, a progressively-revolving feed-wheel connected with said work-holder to move the same progressively lengthwise of the buttonhole, said wheel provided with abutments h' and h² in the path of roller g³ on lever g whereby the lock-bar e is unseated and the lever B' tilted under the action of its spring as set forth and the lock-bar l' moved to stop the vibration of the needle-bar, means for simultaneously stopping therewith the feed motion of the work-holder lengthwise of the buttonhole, and mechanism for progressively moving said work-holder crosswise and simultaneously reciprocating the same lengthwise of the buttonhole while the needle-bar reciprocates only, for the purpose set forth.

14. In a buttonhole-sewing machine, the combination with the main driving-shaft, a right and left threaded sleeve revolving with and having endwise motion on said shaft, the T-lever B', the bell-crank lever B rocked by said lever B', the lock-bars e and l' respectively connected with the arms of lever B, the lever g engaging the lower end of lock-bar e, said bar provided with an offset seating on a fixed support, and the lever i extending through a slot in lock-bar e and provided with a depending pin i⁴; of the stitch-forming appliances comprising a reciprocating and vibrating needle-bar, the work-holder comprising a carrier-slide having motion lengthwise and crosswise of the buttonhole and provided with the slots k' k², the work-holder proper having motion with said slide and independently thereof lengthwise of the buttonhole, the progressively-revolving feed-wheel h having feed-groove m, feed-flange n, and abutments h' h² in the path of the roller g³ on lever g, and suitable connections between the work-holder and the said feed groove and

flange, respectively, substantially as and for the purpose set forth.

15. In a buttonhole-sewing machine, the combination with the stitch-forming appliances comprising a reciprocating and vibrating needle-bar, the work-holder, feed mechanism for imparting to said work-holder a progressive motion lengthwise of the buttonhole, and a lock-bar for locking the needle-bar against vibration; of the main driving-shaft, a right and left threaded sleeve revolving with and having endwise motion on said shaft, the T-lever B' having teeth c c', the latter held in engagement with said left-threaded portion of the sleeve, the abutment a⁵ thereon in the path of said tooth and whereby said lever is tilted to move tooth c out of engagement with the left-threaded portion 85 and tooth c' into engagement with the right-threaded portion of the sleeve, means for maintaining said engagement, and a second lever rocked by lever B' and moving the lock-bar to release the needle-bar, for the purpose 90 set forth.

16. The combination with the stitch-forming appliances, the slides S and q connected to allow slide q to move independently of slide S lengthwise thereof; of the work-holder its carrier q^X, means for reciprocating the same lengthwise of slide q and means for locking carrier q^X to slide q by frictional contact, for the purpose set forth.

17. The combination with the stitch-forming appliances, the slides S and q connected to allow the slide q to move independently of slide S lengthwise thereof; of the work-holder its carrier q^X provided with an elongated concave recess in its upper face, means for reciprocating said carrier lengthwise of slide q, the lock-plate r hinged to the latter and provided with a convex boss r² seated in the aforesaid recess in carrier q^X, and a spring exerting its power on said lock-plate, for the purpose set forth.

18. The combination with the slides S and q connected to allow slide q to move independently of slide S lengthwise thereof, the work-holder comprising the carrier q^X carrying the work-plate and provided with a concave recess in its upper face, a clamping-jaw pivoted to said carrier and provided with a stud on each side, a support s for said jaw having its outer end forked, the arms of the fork being slotted longitudinally for the reception of the studs on the jaw, said support hinged to slide q, the lock-plate r hinged to the pintle of the support and having bearing on slide q^X, and the spring r' interposed between the rear end 120 of support s and said lock-plate, for the purpose set forth.

In testimony that I claim the foregoing as my invention I have signed my name in presence of two subscribing witnesses.

JULIUS GUTMANN.
